FUSE

Charles C. Lauritsen, Pasadena, Calif., assignor
to the United States of America as represented
by the Secretary of the Navy

Application April 2, 1943, Serial No. 481,646

3 Claims. (Cl. 102—81.2)

1

This invention relates to fuzes and more particularly to a novel propeller-armed, impact-fired fuze which is simple and compact in construction and positive and reliable in operation. The new fuze may be handled safely and by reason of its propeller arming it may be used to advantage in rocket-propelled projectiles, and the like, wherein setback forces alone are too small to be employed safely for arming, and centrifugal forces for arming are lacking.

One object of the present invention resides in the provision of a propeller-armed fuze of novel construction including safety means for locking the propeller against rotation and operable by a force of setback to release the propeller.

Another object of the invention is to provide a novel fuze having a firing pin normally holding a safety gate in its safe position and movable endwise by the propeller to release the gate and expose one end of the pin at the nose of the fuze, and means operable on release of the gate to move it to an armed position at one end of the firing pin, whereby the pin is movable endwise into the gate upon impact with a target.

Still another object of the invention is to provide a fuze of the character described having novel safety means for insuring safe handling of the fuze and adapted to be released manually when the fuze is to be fired.

These and other objects of the invention may be better understood by reference to the accompanying drawings in conjunction with the following detailed description. In the drawings

Fig. 1 is a longitudinal sectional view of one form of the new fuze;

Fig. 2 is a sectional view on the line 2—2 in Fig. 1;

Fig. 3 is a longitudinal sectional view of a modified form of the fuze, and

Fig. 4 is a sectional view on the line 4—4 in Fig. 3.

The fuze shown in Figs. 1 and 2 comprises a hollow cylindrical casing 10 having an externally threaded course 11 adapted to be screwed into a suitable receptacle in the nose of an explosive projectile (not shown). At its rear end, the casing is internally threaded to receive a container 12 for the usual booster charge (not shown) through which the main charge in the projectile is detonated. A disc 13 in the casing closes the front end of the booster container 12 and has a central opening 14 through which the booster charge is ignited. A liner 15 abuts at its rear end against the disc 13 and is held in position in the casing by a set screw 16. In front of the liner

2

15 is a guide plate 17 which is held in position between the rear end of the liner and a shoulder 18 in the casing, the guide plate, liner and disc 13 defining a chamber 15a.

5 A safety gate 20 is mounted in the chamber 15a on a pivot 21, so that the gate may swing transversely of the casing. Intermediate its ends, the gate is provided with a passage 22 for receiving a semi-cap (not shown) which may be 10 of any desired form. A spring 23 is coiled around the pivot 21 and normally urges the safety gate clockwise (Fig. 2) against one side of a firing pin 24 slidable in guide plate 17, the firing pin being threaded through the closed front end 15 of the casing, as shown at 25. Thus, the rear end portion of the firing pin normally holds the safety gate 20 in a position wherein a semi-cap recess 22 is offset laterally from the firing pin and the opening 14, so as to prevent accidental 20 firing of the semi-cap and explosion of the booster. In the front face of gate 20 is a plunger 26 which is urged against the adjacent face of guide plate 17 by a compression spring 27 in the gate.

25 A hub 30 is keyed to the front end of the firing pin 24, as by means of a cotter pin 31, and carries a propeller 32. The propeller is normally locked against rotation by a pin 33 extending through the front end of the casing and secured to a set-

30 back pellet in the form of a collar 34 slidable endwise in the casing, the firing pin projecting loosely through the collar. A compression spring 35 is coiled around the firing pin within the collar and is seated at one end against guide plate 17 35 and at the opposite end against a shoulder in the collar, the spring urging the collar against the front end of the casing. The guide plate has a hollow boss 36 projecting into the spring 35 for locating it.

40 An annular shield 38 extends around the propeller 32 and is connected to an external flange 39 on the casing by screws 40. The shield 38 is formed with openings 41 which allow a flow of air against the propeller blades and through the 45 shield. A safety wire 42 is bent around the shield and extends through one of the openings 41 and through alined openings in the casing, where the wire is seated in an annular groove 43 in the set-back collar. The wire 42 prevents accidental 50 movement of the set-back collar against spring 35 so that pin 33 positively locks the propeller against rotation at all times in handling the fuze. Accordingly, the firing pin 24 is maintained in 55 position to prevent movement of the safety gate 20 from its safe position, as shown in Fig. 2.

When a projectile containing the fuze is to be fired, wire 42 is removed from the casing to release the set-back collar 34.

In firing the projectile, the force of set-back incident to its acceleration causes collar 34 to move rearwardly against spring 35, thereby withdrawing the pin 33 from hub 30 and unlocking the propeller. The compression in spring 35 is such that the set-back collar 34 is operable to unlock the propeller in response to a relatively small force of set-back, such as that encountered in the firing of rockets. When the propeller 32 is unlocked, it is rotated aerodynamically incident to the flight of the projectile through the air and screws firing pin 24 forwardly in the casing to disengage the safety gate 20. Accordingly, the gate 20 is released and the spring 23 moves it inwardly against a stop 45 to an armed position wherein the semi-cap opening 22 is alined with and directly under the firing pin. The gate is locked in this position by the spring pressed plunger 26 which moves into an opening 46 in the rear face of guide plate 17. When the projectile strikes a target, the impact on the exposed front end of the firing pin 24 moves the pin rearwardly against the semi-cap in opening 22, shearing the threads 25 on the firing pin. As a result, the semi-cap is fired and detonates the booster through opening 14.

The fuze shown in Figs. 3 and 4 comprises a generally frusto-conical casing 48 which is externally threaded at its rear end, as shown at 49, so that the casing is adapted to be screwed into a receptacle in the nose portion of a projectile (not shown). The fuze receptacle in the projectile may be sealed by a gasket 50 seated on an external shoulder of the casing 48. A container 51 is threaded in the rear end of the fuze casing for receiving a booster charge (not shown) operable to detonate the main charge in the projectile. The booster charge is adapted to be fired by a semi-cap 52 mounted in an axial passage in the fuze casing.

Intermediate its ends, the casing 48 has a transverse cylinder 54 containing a safety gate 55, the gate having an opening 56 extending lengthwise of the casing. The gate 55 is urged inwardly in the cylinder by a compression spring 57 disposed between the outer end of the gate and a plug 58 threaded in the cylinder.

A plunger 60 extends transversely into the fuze casing at right angles to the cylinder 54 and normally engages the inner end of gate 55 so as to hold the gate in a retracted position against spring 57. On its outer end, the plunger 60 has a head 61 engaging one end of a compression spring 62 coiled around the plunger in the fuze casing, the opposite end of spring 62 being seated against a shoulder in the casing. The plunger 60 is formed intermediate its ends with an opening 63 extending lengthwise with respect to the casing and substantially smaller in diameter than the gate opening 56. Near its inner end, the plunger 60 has a notch 64 which receives part of a locking pin 65 extending lengthwise of the casing and rotatable therein. The pin 65 normally locks the plunger 60 against spring 62 in position to hold the gate 55 retracted, but the pin is rotatable through an angle of substantially 90° to release the plunger. Rotation of the pin 65 from its locking position is normally prevented by an arm 66 on the pin which engages one side of a firing pin 67 slidably mounted in an extension 68 of the casing threaded in the front end thereof. At its rear end, the firing pin 67 is reduced and

extends into opening 63 in the plunger so as to provide a supplemental locking means for preventing outward movement of the plunger by spring 62. The opening 63 is smaller in diameter than the main body of the firing pin so that the latter cannot move completely through the plunger, whereby accidental movement of the firing pin against semi-cap 52 is prevented.

The front end portion of the firing pin is threaded through a plate 69 secured in the front end of the casing extension 68, and a hub 70 is screwed on the threaded portion of the pin and keyed to the pin, as shown at 71. A propeller 72 is connected to hub 70 and is normally locked against rotation by a pin 73 projecting rearwardly through the plate 69 and secured in a set-back collar 74 extending loosely around the firing pin. The collar 74 is slideable endwise in casing extension 68 and is urged against plate 69 by a compression spring 75 coiled around the firing pin between a shoulder in the casing extension 68 and a shoulder in the collar, whereby the locking pin 73 is held in position to prevent rotation of the propeller. A safety wire 76 extends transversely through casing extension 68 and engages the rear end of collar 74 to prevent accidental releasing of the propeller in handling the fuze, the safety wire being removable manually to unlock the set-back collar 74 when the fuze is to be fired.

An annular shield 78 extends around the propeller and has an inwardly turned portion 78a clamped between a shoulder on the casing extension 68 and a washer 79 on the front end of casing 48. The shield 78 is provided with openings 80 for the passage of air through the shield when the projectile is in flight.

In operation, when a projectile containing the fuze is fired, the resulting force of set-back moves collar 74 rearwardly against spring 75 so as to withdraw the locking pin 73 from the propeller. It will be understood that the spring 75 is sufficiently yielding to permit movement of the set-back collar under the relatively small set-back forces encountered in rocket-propelled projectiles. When the propeller is thus released, it is rotated aerodynamically during the flight of the projectile through the air and screws firing pin 67 forwardly in casing extension 68. As a result, the firing pin moves out of plunger opening 63 and disengages arm 66 of the locking pin 65, whereupon the plunger 60 is released and forced out of the casing by spring 62. The safety gate 55, therefore, is unlocked and moves inwardly to an armed position under the action of spring 57. In the armed position of the gate, the opening 56 is alined with the firing pin and the semi-cap 52. When the projectile strikes a target, the impact on the exposed front end of firing pin 67 forces the pin to the rear through gate opening 56 against the semi-cap, the impact being sufficient to shear the threads on the front end portion of the firing pin. The semi-cap is then fired and detonates the booster charge in container 51.

The set-back collar 74 prevents accidental rotation of the propeller due to a strong wind or to the blast from an adjacent rocket motor, and the collar may be locked in its safe position by the safety wire 76 at all times when the fuze is not in use. If desired, accidental movement of the pin 65 from its locking position may be prevented by an additional safety wire 82 extending transversely through the fuze casing and the locking pin. The firing pin 67 serves the dual function 75 of firing the semi-cap 52 and preventing move-

ment of the locking pin 65 and safety plunger 60 until the firing pin has been moved to its armed position by rotation of the propeller. If, for any reason, the arm 66 on locking pin 65 should fail to engage the firing pin, the latter continues to hold the plunger 60 in position to prevent movement of the safety gate to its armed position.

I claim:

1. A fuze comprising a hollow body, a firing pin threaded in the body, a propeller connected to the pin and operable aerodynamically to screw the pin to a retracted position in which the front end of the pin is exposed at the nose portion of the fuze, the pin being operable by impact of said end with a target, an inertia-operated collar oriented on the axis of the body through which collar the pin is movable, a locking element on the collar adapted to hold the propeller against rotation, and a spring coiled around the pin for pushing the collar and locking element toward the propeller to lock the propeller against rotation, the collar being movable against the spring by a force of setback to cause said element to release the propeller.

2. In a fuze having a firing pin, a safety gate coacting with the firing pin and having a percussion cap recess, a plunger adjacent one end of the gate and normally locking the gate in an unarmed position wherein said recess is offset from the firing pin, the plunger being held in its locking position by the firing pin, spring means for moving the plunger from its locking position and for moving the gate to an armed position to align said recess with the pin, means normally holding the plunger in its locking position and having a part engaging the firing pin to maintain said means operative, a propeller connected to the firing pin and rotatable aerodynamically to move the pin and thereby release the plunger and said

means, means for normally locking the firing pin against rotation, and inertia-operated means for releasing the locking means.

3. In a fuze having a firing pin, a safety gate coacting with the firing pin and having a percussion cap recess, a plunger adjacent one end of the gate and normally locking the gate in an unarmed position wherein said recess is offset from the firing pin, the plunger being held in its locking position by the firing pin, spring means for moving the plunger from its locking position and for moving the gate to an armed position to align said recess with the pin, means normally holding the plunger in its locking position and having a part engaging the firing pin to maintain said means operative, a releasable safety wire for securing said means against movement, a propeller connected to the firing pin and rotatable aerodynamically to move the pin and thereby release the plunger and said means, means for normally locking the firing pin against rotation, and inertia-operated means for releasing the locking means.
